UNITED STATES PATENT OFFICE.

HENRY BOOT, OF PHILADELPHIA, PENNSYLVANIA, ASSIGNOR TO THOMAS DOLAN AND R. WILLIAMS, JR., OF SAME PLACE.

DESIGN FOR NUBIA.

Specification forming part of Design No. 7,564, dated July 21, 1874; application filed July 10, 1874.
[Term of Patent 3½ years.]

To all whom it may concern:

Be it known that I, HENRY Boot, of Philadelphia, Pennsylvania, have invented a Design for a Nubia, of which the following is a specification:

My design for a nubia is clearly illustrated by the figure in the accompanying drawing, in which are shown a portion of the body A and border B, the latter consisting of coarse scalloped threads interlocked with the finer threads of the body of the fabric, which consists, as usual, of open-work loops.

The body is ornamented by parallel stripes D, each consisting of two or more scalloped

threads coarser than and interlocked with the threads of the body, and of the same or of a different shade or color.

Irrespective of the colors employed, I claim—

The design for a nubia, with its ornamental border B and stripes D, all as described and as represented by the drawing.

In testimony whereof I have signed my name to this specification in the presence of two subscribing witnesses.

HENRY BOOT.

Witnesses:

CLINTON M. LATOURETTE,
LEWIS G. GODFREY.
